CORE CLAMP

Herman R. Korte, Fort Wayne, Ind., assignor to
General Electric Company, a corporation of
New York

Application December 27, 1940, Serial No. 371,919

3 Claims. (Cl. 175—356)

The present invention relates to electrical induction apparatus having a magnetic core structure including a stack of punched laminations and more particularly to clamping means for such core structures.

Some type of a clamping arrangement is required for punched laminations of the magnetic structure of iron cored induction devices for minimizing losses, reduction of noise and for other reasons well known in the art. In the case of small size devices of certain types that are manufactured in large quantities, the clamping arrangements now in general use represent a disproportionate percentage of the total cost of the unit. Not only are the component parts quite expensive but they furthermore do not lend themselves to rapid and accurate assembly in the production lines and hence, the manufacturing costs for such units are relatively high.

It is therefore an object of the present invention to provide a new and improved clamping arrangement for laminated magnetic core structures of the electrical induction apparatus which is low in manufacturing cost and which facilitates the assembly of the apparatus units.

It is a further object of the present invention to provide a new and improved core clamp which is particularly suitable for laminated structures of the type wherein adjustments are required to be made in the assembly of the apparatus units.

It is a still further object of the present invention to provide a new and improved clamping means for laminated magnetic core structures of the shell type.

It is a further object of the invention to provide a new and improved core clamp comprising a minimum number of parts, simple in design, light in weight, and of relatively great rigidity.

Further objects and advantages of the invention will appear from the following description and the claims appended thereto taken in connection with the accompanying drawing.

In the drawing, Fig. 1 is a plan view of a transformer device having a laminated magnetic core which is provided with a clamping means according to the invention; Fig. 2 is an enlarged cross sectional view of a portion of the transformer device of Fig. 1 taken along the line 3—3; Fig. 3 is a view of the transformer device mounted within an enclosing casing, the casing being shown in section; and Fig. 4 is a view in perspective of one of the clamping frames of the invention.

The core clamps of the present invention will

be described as applied to a transformer auxiliary device of the type used for supplying operating voltages to gaseous discharge lamps in what is commonly known in the art as a "Tu-lamp" circuit. It will be obvious, however, that the core clamps may be equally well applied to other electrical induction apparatus.

The transformer auxiliary device shown comprises a transformer unit 10 and a pair of inductive reactance units 11 and 12 arranged adjacent the opposite ends of the transformer unit. The transformer unit 10 includes a winding coil 13 arranged upon the central leg 14 of the rectangular laminated shell type core which also includes the outer legs 15 and 16 and the end yoke portions 17 and 18. The two reactance units 11 and 12 may be of generally similar construction comprising winding coils 19 and 21 arranged upon the central leg of laminated E-shaped cores 22 and 23, respectively. The reactance units are arranged adjacent the opposite ends of the transformer unit with gaps provided between the ends of the E-legs and the adjacent end yokes of the transformer core. Non-magnetic spacers 24 and 25 of some suitable material such as fiber are preferably arranged within the gaps. The stacks of laminations forming the cores for the transformer and the two reactance units are preferably of substantially the same height so that when they are arranged in an end-to-end relation, as shown, the opposite sides thereof lie in substantially common planes.

The illustrated transformer device is held together in the assembled position by a pair of similar clamp members 26 and 27, one of which is shown in greater detail in Fig. 4. Each of the clamp members consists of a stamped sheet metal frame of a substantially rectangular configuration and conforming with the contour of the outer core legs and yokes as illustrated in Fig. 1. Thus, the frames may take any suitable shape depending upon the contour of the surface with which it is to cooperate, and in the illustrated embodiment of my invention it will be seen that the frames are of a substantially rectangular shape with rounded corners. These frames are stamped from one side into a channel cross sectional shape throughout their respective lengths. The channel sides 28 and 29 extend substantially at right angles with respect to the flat intermediate portion 31. For imparting maximum rigidity to the clamp members, the two channel sides are continuous throughout the inner and outer circumferential

lengths respectively of the clamp members, the corners being furthermore suitably rounded not only for facilitating the stamping operation but also for the purpose of improving the stress distribution as will be more fully explained herein-after. After the stamping operation is completed, the edges of the channel sides may be trimmed, if necessary, in order that the edges will lie in a substantially common plane throughout the channel sides. The two clamping members are placed against the opposite sides of the core structure with the edges of the channel sides against the flat or longitudinal surface of the laminations, it being understood that the width of the channel of the clamp members is somewhat less than the width of the outer core legs and yokes of the core structure. The two clamp members are forced together by means of a pair of bolts 35 and 36 which extend through cooperating holes provided in the yokes of the E laminations of the reactor units 11 and 12. The cooperating openings in the clamp members being in substantial registry with the holes or apertures in the yokes are elongated in the direction of the core axis in order to permit adjustment of the non-magnetic gaps in a manner to be presently described. Suitable washers 37 are provided between the head and nut of the bolt and the clamping members. Thus, each of the frame members has a generally ring-like shape with straight sides connected by wholly rounded corners and has a substantially uniform channel shape cross section at all points around its periphery so that the core members may be clamped tightly together.

Because of the channel cross sectional shape of the clamp members, they will be very rigid due to the fact that the channel sides thereof extend edgewise with respect to the core surfaces. So great is their rigidity that only two bolts are required, as shown, for securely clamping together a core structure of the type herein described comprising three separate lamination stacks. By providing rounded corners for the clamp members there is no such concentration of stress as might cause bending of the clamp members at these points, and as a result, tightening of the bolts at the opposite ends of the assembly will exert sufficient compressive force between the clamp members throughout their length so as to adequately clamp together the laminations of the intermediate transformer unit as well as those of the reactor units.

After the unit has been assembled, the leads of the various windings may be connected to indicating instruments of the testing apparatus (not shown), and the operational characteristics of the device may be adjusted, if necessary, by slightly varying the spacing of the non-magnetic gaps through the use of any suitable means. It will be readily understood by those skilled in the art that even though a non-magnetic spacer 25 is selected of such a predetermined thickness which should give the required gap spacing, further adjustment of the gap may be necessary depending upon the degree of accuracy required in the finished product. Such adjustment may be accomplished by simply tapping the appropriate end of the device with a small mallet, variously comprising the fibrous spacer 24 or 25 until the exact desired indication is obtained on the test instruments. By reason of the slightly elongated holes provided in the core clamps, the cores of the two reactance units

may be shifted somewhat for effecting the adjustment of the non-magnetic gaps relative to the transformer core. Since the bolts 35 and 36 extend laterally or at right angles with respect to the lamination stacks, there will be no tendency on the part of these bolts to alter the non-magnetic gap spacing once it has been adjusted. The contact friction between the edges of the clamp members and the laminations will hold the cores firmly and maintain the gap as adjusted throughout the remainder of the assembly operation.

The transformer device may now be mounted within an enclosing housing 39, as shown in Fig. 15, 3, which may then be filled with a suitable insulating compound indicated at 40, substantially filling the housing after which the cover 41 may be applied.

It will be apparent that the clamping arrangement of this invention is extremely simple and of low manufacturing cost, and yet at the same time may be adapted for clamping relatively complicated core structures, such as that shown. The clamping device serves not only for fastening together the laminations of a number of individual core stacks, but because of the great rigidity of the clamp members, it may also be utilized for securing the plurality of core stacks relative to each other in a predetermined spaced relation.

Having described my invention in what I consider to represent a preferred embodiment thereof, I desire to have it understood that the specific structure shown is merely illustrative and that the invention may be carried out by other means.

What I claim as new and desire to secure by Letters Patent of the United States is:

1. A clamp for a stack of magnetic core laminations having outer core legs and yokes comprising a pair of stamped sheet metal frame members, each of said members having a generally rectangularly ring-like shape with straight sides connected by wholly rounded corners and conforming to the contour of the outer legs and yokes, each of said members having substantially uniform channel shaped cross section of less width than that of the legs and yokes at all points around its periphery, the edges of the channel sides being continuous and terminating in a common plane for engaging with the opposite substantially plane sides of the outer core legs and yokes, and means including bolts extending perpendicularly of said plane sides between opposite portions of said channels for forcing said channels toward each other to tightly secure said laminations together.

2. In combination with an electrical induction apparatus having a substantially rectangular laminated magnetic core with outer legs and yokes, a pair of clamping members for said core each comprising a stamped substantially rectangularly ring-like shaped sheet metal frame with straight sides connected by rounded corners and conforming to the contour of the outer legs and yokes, each of said frames having a substantially uniform channel shaped cross section at all points around its periphery, each of said frames around its periphery having a width less than the width of the outer legs and yokes and continuous edges terminating in a common plane so that the channel edges of said frames will engage said outer legs and yokes of said substantially rectangular core, and means for clamping

said clamping members against the opposite faces of said outer legs and yokes.

3. In combination with an electrical induction apparatus having a substantially rectangular shell type laminated core, a pair of clamping members for said core each comprising a stamped substantially rectangularly ring-like shaped sheet metal frame with straight sides connected by wholly rounded corners, said

5 frames including said corners having a substantially uniform channel shaped cross section of less width than that of the legs and yokes at all points around its periphery with continuous edges terminating in a common plane, and clamping means for forcing said frames against opposite surfaces of said core with the channels of said frames facing said core.
